DESIGN FOR AN ASH TRAY

Charlotte Tremper Armus, New York, N. Y.

Application January 8, 1947, Serial No. 136,000

Term of patent 7 years

(Cl. D85—2)

To all whom it may concern:

Be it known that I, Charlotte Tremper Armus, a citizen of the United States, residing in New York city, county of New York, and State of New York, have invented a new, original, and ornamental Design for an Ash Tray, of which the following is a specification, reference being had to the accompanying drawing, forming part thereof.

In the drawing:

Figure 1 is a top view of an ash tray constituting my design.

Figure 2 is a side view of the ash tray shown in Figure 1.

Figure 3 is a section along the line 3—3 of Fig. 1.

I claim:

The ornamental design for an ash tray, as shown.

CHARLOTTE TREMPER ARMUS.
